ALTITUDE COMPENSATOR

Walter F. Isley, Detroit, Mich., assignor to Continental Motors Corporation, Muskegon, Mich., a corporation of Virginia

Application September 21, 1955, Serial No. 535,693

12 Claims. (Cl. 123—140)

My invention relates to a fuel injection control means for the purpose of controlling the operation of fuel injection pumps and specifically to the actuation of such means in relation to atmospheric pressure changes at varying altitudes.

In the development of fuel injection pump controls, major problems are involved in developing means for insuring the most economical and most efficient fuel-air ratios, which are dependent on changes in engine volumetrics efficiencies under varying operating conditions. Although many injection pump control devices which are sensitive to manifold pressures have proven satisfactory in improving engine performance and fuel economy, heretofore a definite need existed for a simple and efficient automatic device which can maintain most desirable fuel-air ratios under varying engine operating conditions at changing altitudes. Basically, existing fuel injection control means fail to sense the increase in volumetric efficiency with increasing altitude at constant manifold pressure. The increase in volumetric efficiency of the engines is caused by a reduced exhaust back pressure due to a decrease of atmospheric pressure at altitudes above sea level. Without altitude sensitive control, the fuel rate remains in essentially constant relation to manifold pressures, which decrease with altitude due to lower atmospheric pressures, and the injector therefore is calibrated to follow a normal metering curve, i. e. a reduction in pump fuel output. Hence, as altitude increases, the lowering fuel rate, in combination with the engine's higher volumetric efficiency, results in abnormally low fuel-air ratios or an over lean mixture, thereby preventing optimum engine performance.

An object of my invention, therefore, is to improve the operating characteristics of fuel-injection engines at varying altitudes by providing an altitude compensating device to modify the manifold pressure control of the fuel injection pump.

Another object of my invention is to obtain a desired "best power" fuel-air ratio condition at full throttle conditions and a "best economy" fuel-air ratio condition at part throttle operating conditions regardless of altitude by providing an altitude compensating device which will modify manifold pressure control of the fuel injection pump in differing degree at varying throttle conditions and altitudes.

For a further understanding of my invention, reference may be had to the accompanying drawing which illustrates two preferred embodiments of my invention, and in which like characters refer to like parts throughout the several views, and in which

Fig. 1 is a vertical elevational view of a conventional fuel injection pump with pressure control devices installed.

Fig. 2 is a cross section elevational view on line 2—2 of Fig. 1, illustrating one embodiment of my invention.

Fig. 3 is a similar view on line 2—2 of Fig. 1, illustrating a different operating position of the mechanism.

2

Fig. 4 is another similar view on line 2—2 of Fig. 1. Fig. 5 is a section on the line 4—4 of Fig. 2.

Referring to the drawing in more detail, Fig. 1 shows a conventional engine air induction system 10 having a throttle valve 11 and a supercharger 12. An engine driven variable delivery fuel injection pump 13 of conventional design is shown with its controlling devices mounted thereon, comprising a servo valve 14, an altitude compensator 15, and a pressure sensitive control 16. A conduit 17 connects the altitude compensator 15 with the air induction system 10 on the atmosphere or upstream side of the throttle 11. Another conduit 18 connects the compensator 15 with the air induction system 10 on the manifold pressure or downstream side of the throttle 11 and the supercharger 12. The output of the pump 13 is dependent on the actuation of the servo valve 14 by well known means which are familiar to those skilled in the art and which form no part of the invention herein described.

Fig. 2 shows one type of altitude compensator 15 designated as a dual piston altitude compensator, adjoining and suitably secured or connected to the pressure sensitive control 16 which is shown in part. The pressure sensitive control 16 comprises a housing 20 having a pressure control chamber 21 and supporting a pressure sensitive bellows assembly 22. A pin shaft 23 is connected at one end to the bellows assembly 22 and at the other end to the servo valve 14 (as shown partially in detail in Fig. 2). Actuation of the pin shaft 23 to the right or outwardly as viewed in Fig. 2 affects the servo valve to decrease the fuel output of the pump, providing lean fuel metering characteristics. Actuation of the pin shaft 23 to the left or inwardly affects the servo valve to increase the fuel output of the pump providing rich fuel metering characteristics. The position of the pin 23 is determined by compression and expansion of the bellows assembly 22. This, in turn, is due to the effective changes of air pressure existing in control chamber 21. In essence, the air pressure in control chamber 21 is the manifold pressure of the engine, introduced through suitable connections. However, the manifold pressure is modified and controlled by devices which are fully described and claimed in my copending application Serial No. 370,535, filed July 27, 1953, now Patent 2,759,469, issued Aug. 21, 1956 and copending application Serial No. 370,593, filed July 27, 1953, now Patent 2,749,898, issued June 12, 1956, both of which are entitled "Fuel Injection Control."

The altitude compensator 15 is suitably mounted between the pressure sensitive control 16 and the servo valve 14. It comprises a piston housing 24 having a throttle inlet pressure tap 25 open to conduit 17 and a manifold pressure tap 26 open to conduit 18. A central chamber in the piston housing 24 has two portions, namely an altitude pressure chamber 27 and a manifold pressure chamber 28, separated by a large free-floating power enrichment piston 30, which is slidably mounted on the pin shaft 23. A small auxiliary piston 31 is fixed to the pin shaft 23 and is set within a recess 32 of the large piston 30. A passage 33 in the piston housing 24 connects the throttle inlet pressure tap 25 to the altitude pressure chamber 27. Another passage 34 in the piston housing 24 connects the manifold pressure tap 26 with the manifold pressure chamber 28. Passages 35 in the free floating piston 30 open the recess 32 on the inner side of the small piston 31 to the manifold pressure chamber 28.

The operation of the pressure sensitive control 16, described in my copending applications aforementioned causes a shift of the pin shaft 23 either to right or left resulting in a change of fuel metering characteristics and hence fuel-air ratios. The degree of shift is determined by the air pressure in the control chamber 21, and also

by the total effective area of the bellows assembly 22. In effect, the altitude compensator of this invention is so adapted to increase the effective area of the bellows assembly 22 at higher altitudes in order to achieve increased fuel flow. This is accomplished as follows:

At part throttle positions, when manifold pressures are relatively low, the atmospheric pressure in the altitude pressure chamber 27 forces the free floating piston 30 to the right, or away from the small piston 31, as illustrated in Fig. 3, at which position the free floating piston 30 produces no effect on the control characteristics of the bellows 22. The small piston 31, however, being fixed to the pin shaft 23, produces a change in the control characteristics of the bellows 22 in direct relationship to the pressure existing in the altitude pressure chamber 27. Due to the connection of this chamber 27 with the engine air induction system 10 upstream of the throttle valve 11 where atmospheric pressure exists, the pressure in chamber 27 will decrease with any altitude increase due to the corresponding decrease in atmospheric pressure. The manifold pressure existing in chamber 28, passing through passages 35 to that portion of the recess 32 behind or to the right of the piston 31, acts on the piston 31 with a force increasing as altitude increases. In other words, increase in altitude causes an increase in differential of pressures introduced at opposite sides of the small piston 31. Thus, as the altitude increases, a shift to the left of the pin shaft 23 results, causing the servo valve 14 to which it is connected to effect an increase in the fuel output of the pump 13, i. e. to effect a change toward the richer fuel metering characteristics. As altitude decreases, the atmospheric pressure in the altitude chamber 27 increases, causing a shift of the pin shaft 23 to the right, then reducing the pump fuel output.

At full power engine operation, the manifold pressure, and hence the pressure in the manifold pressure chamber 28, increases sufficiently to force the free-floating piston 30 to the left as illustrated in Fig. 2, so that the inner face of the recess 32 bears against the smaller piston 31. In effect, this motion of the large piston 30 actually increases the effective area of the small piston 31, so that when altitude increases and the pressure in the altitude chamber decreases, a greater degree of shift to the left or to the rich fuel metering characteristics occurs than can be caused by the small piston 31 alone.

Thus it can be seen that the effective areas of the two pistons can be so constructed to provide the required "best power" fuel-air ratio at full throttle operating conditions, and "best economy" fuel-air ratio at part-throttle operating conditions when operating at various altitudes, since the degree of shift will depend on the respective areas of the two pistons.

In Fig. 4, a modification of the embodiment shown in Fig. 2 is shown, and is designated as a single piston altitude compensator, in which everything is identical with Fig. 2 except that a single piston 40 replaces the dual pistons 30 and 31. The operating characteristics of this type of compensator is the same as described for the compensator of Fig. 2 for engine full power operation. This altitude compensator is useful in applications for which fuel economy at part throttle is not required. The effective area of piston 40 is essentially the same as the effective area of piston 30 when piston 30 is bearing against piston 31, as explained above.

While I have illustrated but two embodiments of my invention, it will be apparent, however, to those skilled in the art to which my invention pertains, that various changes and modifications may be made therein without departing from the spirit of my invention or from the scope of the appended claims.

I claim:

1. In an internal combustion engine having an air induction system including an air intake manifold and a throttle valve associated therewith, a variable delivery fuel injection pump, and a pump control means operable

to vary the fuel metering of said pump and comprising a pressure sensitive actuator operable only in response to variations in manifold pressure and an altitude compensator operable in response to variations in pressure differential between manifold pressure and atmospheric pressure to modify the operation of said actuator, and means operatively connecting said actuator with said altitude compensator, whereby to compensate for decreased sensitivity of said actuator due to an increase in altitude, and means selectively actuated in response to an increase in the aforesaid pressure differential beyond a predetermined value to increase the modifying effect of said altitude compensator on said actuator for high speed engine throttle operation, said last mentioned means being inoperative when the aforesaid manifold pressure is below said predetermined value.

2. In an internal combustion engine having an air induction system including an air intake manifold and a throttle valve associated therewith, a variable delivery fuel injection pump, and a pump control means operable to vary the fuel metering of said pump and comprising a plurality of interconnected pressure sensitive instrumentalities operatively connected to said pump, one of said instrumentalities operable only in response to variations in manifold pressure, and another of said instrumentalities operable in response to variations in pressure differential between manifold pressure and atmospheric pressure, said last mentioned instrumentality comprising an element continuously connected to said first mentioned instrumentality and actuated in response to the aforesaid pressure differential variations during all manifold pressure values to modify the operation of said first mentioned instrumentality and a second element selectively actuated in response to an increase in manifold pressure beyond a predetermined value to increase the modifying effect of said first mentioned element on said first mentioned instrumentality for high speed engine throttle operation.

3. In an internal combustion engine having an air induction system including an air intake manifold and a throttle valve associated therewith, a variable delivery fuel injection pump, and a pump control means operable to vary the fuel metering of said pump and comprising a plurality of interconnected pressure sensitive instrumentalities operatively connected to said pump, one of said instrumentalities operable only in response to variations in manifold pressure, and another of said instrumentalities operable in response to variations in pressure differential between manifold pressure and atmospheric pressure, said last mentioned instrumentality comprising an element continuously connected to said first mentioned instrumentality and actuated in response to the aforesaid pressure differential variations during all manifold pressure values to modify the operation of said first mentioned instrumentality relative to altitude variations, and a second element selectively actuated in response to an increase in manifold pressure beyond a predetermined value to increase the modifying effect of said first mentioned element on said first mentioned instrumentality for high speed engine throttle operation, said last mentioned element being inoperative when the aforesaid manifold pressure is below said predetermined value.

4. In an internal combustion engine having an air induction system including an air intake manifold and a throttle valve associated therewith, a variable delivery fuel injection pump, and a pump control means operable to vary the fuel metering of said pump and including an altitude compensator comprising an actuating means operable in response to variations in pressure differential between manifold pressure and atmospheric pressure to modify fuel metering in compensation for changes in engine volumetric efficiency with changes in altitude, and a second actuating means selectively actuated in response to an increase in manifold pressure beyond a predetermined value to increase the aforesaid modifying effect

of said first mentioned actuating means on fuel metering for high speed engine throttle operation.

5. In an internal combustion engine having an air induction system including an air intake manifold and a throttle valve associated therewith, a variable delivery fuel injection pump, and a pump control means operable to vary the fuel metering of said pump and including an altitude compensator comprising an actuating means operable in response to variations in pressure differential between manifold pressure and atmospheric pressure to modify fuel metering in compensation for changes in engine volumetric efficiency with changes in altitude, and a second actuating means selectively actuated only in response to an increase in manifold pressure beyond a predetermined value to increase the aforesaid modifying effect of said first mentioned actuating means on fuel metering for high speed engine throttle operation only, said last mentioned actuating means being inoperative when the aforesaid manifold pressure is below said predetermined value.

6. In an internal combustion engine having an air induction system including an air intake manifold and a throttle valve associated therewith, a variable delivery fuel injection pump, and a pump control means operable to vary the fuel metering of said pump and comprising a housing structure having pressure chambers, one of said chambers being openly connected only to said air intake manifold downstream of said throttle valve and a pressure sensitive actuator supported in said chamber and operable only in response to variation of manifold pressure in said chamber, means operatively connecting said actuator to said pump for varying fuel metering of same relative to changes in manifold pressure, a second pressure sensitive actuator movably supported in another of said chambers and separating same into two pressure compartments, one of said compartments being openly connected only to said air intake manifold downstream of said throttle valve, the other of said compartments being openly connected only to atmosphere, means operatively connecting said second actuator to said first actuator, said second actuator operable in response to variations of pressure differential between the pressures in the two compartments to modify the operation of said first mentioned actuator relative to atmospheric pressure changes due to changes in altitude, whereby to compensate for decreased sensitivity of said actuator due to an increase in altitude, said second actuator comprising a pressure sensitive element continuously operatively connected to said first actuator and actuated in response to the aforesaid pressure differential variations during all manifold pressure values to modify the operation of said first actuator relative to altitude variations, and a second pressure sensitive element selectively actuated in response to an increase in manifold pressure beyond a predetermined value to increase the modifying effect of said first mentioned element on said first actuator for high speed engine throttle operation.

7. In an internal combustion engine having an air induction system including an air intake manifold and a throttle valve associated therewith, a variable delivery fuel injection pump, and a pump control means operable to vary the fuel metering of said pump and comprising a housing structure having pressure chambers, one of said chambers being openly connected only to said air intake manifold downstream of said throttle valve and a pressure sensitive actuator supported in said chamber and operable only in response to variation of manifold pressure in said chamber, means operatively connecting said actuator to said pump for varying fuel metering of same relative to changes in manifold pressure, a second pressure sensitive actuator movably supported in another of said chambers and separating same into two pressure compartments, one of said compartments being openly connected only to said air intake manifold downstream of said throttle valve, the other of said compartments

being openly connected only to atmosphere, means operatively connecting said second actuator to said first actuator, said second actuator operable in response to variations of pressure differential between the pressures in the two compartments to modify the operation of said first mentioned actuator relative to atmospheric pressure changes due to changes in altitude, whereby to compensate for decreased sensitivity of said actuator due to an increase in altitude, said second actuator comprising a pressure sensitive element continuously operatively connected to said first actuator and actuated in response to the aforesaid pressure differential variations during all manifold pressure values to modify the operation of said first actuator relative to altitude variations, and a second pressure sensitive element selectively actuated in response to an increase in manifold pressure beyond a predetermined value to increase the modifying effect of said first mentioned element on said first actuator for high speed engine throttle operation, said last mentioned element being inoperative when the aforesaid manifold pressure is below said predetermined value.

8. In an internal combustion engine having an air induction system including an air intake manifold and a throttle valve associated therewith, a variable delivery fuel injection pump, and a pump control means operable to vary the fuel metering of said pump and comprising a housing structure having pressure chambers, one of said chambers being openly connected only to said air intake manifold downstream of said throttle valve and a pressure sensitive actuator supported in said chamber and operable only in response to variation of manifold pressure in said chamber, means operatively connecting said actuator to said pump for varying fuel metering of same relative to changes in manifold pressure, a second pressure sensitive actuator movably supported in another of said chambers and separating same into two pressure compartments, one of said compartments being openly connected only to said air intake manifold downstream of said throttle valve, the other of said compartments being openly connected only to atmosphere, means operatively connecting said second actuator to said first actuator, said second actuator operable in response to variations of pressure differential between the pressures in the two compartments to modify the operation of said first mentioned actuator relative to atmospheric pressure changes due to changes in altitude, whereby to compensate for decreased sensitivity of said actuator due to an increase in altitude, said second actuator comprising a free-floating piston slidably supported in said other chamber and separating said compartments, and free floating piston having a recess in the side exposed to the compartment connected to atmosphere, a second piston slidably supported in said recess and closing same from communication with said compartment connected to atmosphere, a passage in said free-floating piston and openly connecting said recess with the compartment connected to said manifold, said second piston continuously operatively connected to said first actuator and actuated in response to variations in the pressure differential between atmospheric pressure in said second compartment and manifold pressure in said recess during all manifold pressure values to modify the operation of said first actuator relative to altitude variations, said free-floating piston selectively actuated in response to an increase in manifold pressure beyond a predetermined value to coat with said second piston for increasing the modifying effect of same on said first actuator for high speed engine throttle operation.

9. In an internal combustion engine having an air induction system including an air intake manifold and a throttle valve associated therewith, a variable delivery fuel injection pump, and a pump control means operable to vary the fuel metering of said pump and comprising a housing structure having pressure chambers, one of

said chambers being openly connected only to said air intake manifold downstream of said throttle valve and a pressure sensitive actuator supported in said chamber and operable only in response to variation of manifold pressure in said chamber, means operatively connecting said actuator to said pump for varying fuel metering of same relative to changes in manifold pressure, a second pressure sensitive actuator movably supported in another of said chambers and separating same into two pressure compartments, one of said compartments being openly connected only to said air intake manifold downstream of said throttle valve, the other of said compartments being openly connected only to atmosphere, means operatively connecting said second actuator to said first actuator, said second actuator operable in response to variations of pressure differential between the pressures in the two compartments to modify the operation of said first mentioned actuator relative to atmospheric pressure changes due to changes in altitude, whereby to compensate for decreased sensitivity of said actuator due to an increase in altitude, said second actuator comprising a free-floating piston slidably supported in said other chamber and separating said compartments, and free floating piston having a recess in the side exposed to the compartment connected to atmosphere, a second piston slidably supported in said recess and closing same from communication with said compartment connected to said manifold, said second piston continuously operatively connected to said first actuator and actuated in response to variations in the pressure differential between atmospheric pressure in said second compartment and manifold pressure in said recess during all manifold pressure values to modify the operation of said first actuator relative to altitude variations, said free-floating piston selectively actuated in response to an increase in manifold pressure beyond a predetermined value to coat with said second piston for increasing the modifying effect of same on said first actuator for high engine throttle operation, said free-floating piston being inoperative when the aforesaid manifold pressure is below said predetermined value.

10. In an internal combustion engine having an air induction system including an air intake manifold and a throttle valve associated therewith, a variable delivery fuel injection pump, and a pump control means operable to vary the fuel metering of said pump and comprising a housing structure having axially spaced pressure chambers, one of said chambers being openly connected only to said air intake manifold downstream of said throttle valve and a pressure sensitive actuator supported in said chamber and operable only in response to variation of manifold pressure in said chamber, means operatively connecting said actuator to said pump for varying fuel metering of same relative to changes in manifold pressure, a second pressure sensitive actuator axially aligned with the first mentioned actuator movably supported in another of said chambers and separating same into two axially spaced pressure compartments, one of said compartments being openly connected only to said air intake manifold downstream of said throttle valve, the other of said compartments being openly connected only to atmosphere, means operatively axially connecting said second actuator operable in response to variations of pressure differential between the pressures in the two compart-

ments to modify the operation of said first mentioned actuator relative to atmospheric pressure changes due to changes in altitude, whereby to compensate for decreased sensitivity of said actuator due to an increase in altitude,

- 5 5 a shaft connecting said first actuator to said pump and slidably extending through said second chamber, said second actuator comprising a free-floating piston axially slidably supported in said other chamber and on said shaft and separating said compartments, said free-floating piston
- 10 10 having a recess in the side exposed to the compartment connected to atmosphere, a second piston slidably axially supported in said recess and connected to said shaft, said second piston closing said recess from communication with said compartment connected to atmosphere, a passage in said free-floating piston and openly connecting said recess with the compartment connected to said manifold, said second piston axially actuated in response to variations in the pressure differential between atmospheric pressure in said second compartment and manifold pressure
- 15 15 in said recess during all manifold pressure values to modify the operation of said first actuator relative to altitude variations, said free-floating piston selectively axially actuated in response to an increase in manifold pressure beyond a predetermined value to axially coat with said
- 20 20 second piston for increasing the modifying effect of same on said first actuator for high speed engine throttle operation.

11. In an internal combustion engine having an air induction system including an air intake manifold and a throttle valve associated therewith, a variable delivery fuel injection pump, and a pump control means operable to vary the fuel metering of said pump and including an altitude compensator comprising an actuating means operable in response to variations in pressure differential between manifold pressure and atmospheric pressure to modify fuel metering in compensation for changes in engine volumetric efficiency with changes in altitude, and a second actuating means constructed and arranged to coat with said first actuating means only when manifold pressure increases beyond a predetermined value and to supplement the modifying effect of said first actuating means for high speed engine throttle operation.

- 30 30 12. In an internal combustion engine having an air induction system including an air intake manifold and a throttle valve associated therewith, a variable delivery fuel injection pump, and a pump control means operable to vary the fuel metering of said pump and including an altitude compensator comprising an actuating means operable in response to variations in pressure differential between manifold pressure and atmospheric pressure to modify fuel metering in compensation for changes in engine volumetric efficiency with changes in altitude, and a second actuating means constructed and arranged to coat with said first actuating means only when manifold pressure increases beyond atmospheric pressure and to increase the modifying effect of said first actuating means for high speed engine throttle operation.
